DESIGN FOR A LEATHER BELTING FOR WAIST BELTS OR SIMILAR ARTICLE

Eugene O. Peabody, Fort Washington, Pa.

Application September 8, 1933. Serial No. 49,221

Term of patent 14 years

To all whom it may concern:

Be it known that I, EUGENE O. PEABODY, a citizen of the United States, residing at Fort Washington, in the county of Montgomery and Commonwealth of Pennsylvania, have invented a new, original, and ornamental Design for Leather Belting for Waist Belts or Similar Article, of which the following is a specification, reference being had to the accompanying drawing, forming part thereof, in which:

Fig. 1 is an enlarged face view of a portion of a waist belt or similar article, showing my new design; and

Fig. 2 is a transverse cross-section of Fig. 1.

The white portion indicates one color and the shading, collectively, indicates another color.

From the edges inward the border is a grained surface, and a raised rounded rib with a bridle leather or smooth finish, and the center is a raised true suede finish.

I claim:

The ornamental design for a leather belting for waist belts or similar article, substantially as shown and described.

EUGENE O. PEABODY.
